[57] ABSTRACT

A scaffold in H-frame form combines a telescoping platform and collapsible verticals. Locking means secure the scaffold in two or more telescoped positions.

1 Claim, 8 Drawing Figures

PATENTED JUL 10 1973

FIG. 1

FIG. 3

FIG. 2

FIG. 4

FIG. 6

FIG. 7

FIG. 8

HOME SCAFFOLD

This invention relates to home construction and maintenance, more particularly to scaffolds.

A principal object of this invention is to provide a home scaffold in one hinged unit that opens from its flat storage configuration to an operative position in which two vertically standing members support a platform. The platform comprises two floor members in a telescoping manner for adjusting the distance between the vertical supports. Braces secure the scaffold in either the collapsed or extended platform position.

Another object of this invention is to provide a home scaffold that is light, strong, durable and safe.

These and other objects will be readily evident upon a study of the following specification and the accompanying drawing wherein:

FIG. 1 is a front elevation view in the operative position.

FIG. 2 is an end elevation view of FIG. 1.

FIG. 3 is a bottom view of FIG. 1.

FIG. 4 is a view of the knee brace lock.

FIG. 5 is a plan view of the folded scaffold.

FIG. 6 is a fragmentary section elevation view showing a paint tray adapted for attachment to a rung on the vertical members.

FIG. 7 is a fragmentary enlarged elevation view of the telescoping deck.

FIG. 8 is a front elevation view of the scaffold indicating the extended position in dot-dash outline.

Referring to the figures, the scaffold 10 comprises a working platform 11 spindling at each end a vertical support structure 12 at pins 13.

To steady the scaffold a pair of diagonal braces 14 extend from spindling pins 15 in structure 12 to locking pins 16 on platform 11. To aid in storage, braces 14 are made in a pair of members hinged at pins 17.

The lower end of braces 14 are provided with slotted openings 18 which engage and seat on pins 16.

Platform 11 comprises two floor members 19 and 20, ribbed and fitted to be slid, one in the other, allowing

the scaffold to be lengthened. One or more additional pins 16 as for example, pin 16A, then serve to secure structure 12.

Articles used in home construction, repair or maintenance may be attached in various ways to the scaffold. By example, a paint tray 21 is fitted with a bracket 22 for support from a rung 23 in structure 12. Hooks 24 may be attached for tools. Another hook may be used to hang the scaffold in storage against a wall. Also a carrying handle 25 may be attached.

Folded flat, as in FIG. 5, the scaffold becomes a long platform that can be supported between two ladders for larger jobs around the house.

To prevent marring finished floor surfaces in the house, protective pads 26 are attached to the four verticals in structures 12.

What I claim is:

1. A portable, extendable, and collapsible scaffold device comprising:
20 a pair of one-piece vertical support members, each said member having enlarged portions at the top and bottom ends thereof;
a horizontal platform pivotally connected to each said vertical support member at a point approximately midway between said enlarged portions, said platform comprising a plurality of ribbed platform members adapted to be connected to each other in a telescoping manner;
25 and a pair of foldable diagonal braces respectively connected from said platform to the top enlarged portion of one of said vertical support members, whereby said braces serve in their unfolded position to both steady said scaffold device and reduce the possibility of a user accidentally stepping off of the platform yet in their folded position permit the scaffold device to be collapsed to a rigid and substantially planar configuration for storage or for use as an extended platform between a pair of ladders or the like.
